UNITED STATES PATENT OFFICE

ROBERT N. ROSS, OF ST. LOUIS, MISSOURI, ASSIGNOR, BY DIRECT AND MESNE ASSIGNMENTS, TO THE EUREKA BRICK MACHINE MANUFACTURING COMPANY, OF LOUISVILLE, KENTUCKY.

BRICK-MACHINE.

SPECIFICATION forming part of Letters Patent No. 293,596, dated February 12, 1884.

Application filed February 5, 1883. (No model.)

To all whom it may concern:

Be it known that I, ROBERT N. ROSS, of the city of St. Louis, in the State of Missouri, have invented a certain new and useful Improvement in Brick-Machines, of which the following is a full, clear, and exact description, reference being had to the accompanying drawings, forming part of this specification, and in which—

10 Figure 1 is part in side elevation and part in vertical section. Fig. 2 is a front end view. Fig. 3 is a vertical section, showing the parts in a different position from that shown in Fig. 1. Fig. 4 is a top view. Fig. 5 is a rear end view. Fig. 6 is a perspective view of the charger. Fig. 7 is a perspective view of the lower plunger, and Fig. 8 is a similar view of one of the removable plates which form the faces of the dies of the lower plunger.

20 My invention relates to that class of brick-machines wherein two approaching plungers press the clay in the molds; and my invention consists in points of novelty hereinafter fully described and claimed.

25 Referring to the drawings, A represents the outer casing or housing of the machine, and B the driving-pulley, rigidly secured to a shaft, B', journaled in boxes B², secured to a swinging frame, C, supported on a bolt or rod, C', having bearing at one end in one side of the housing A, and at the other end in a side plate, D, supported by the base D' of the machine.

35 On the shaft B', between the boxes B², and rigidly secured thereto, is a friction driving-roller, E, (see Fig. 1,) which bears against and turns a roller or wheel, F', on a counter-shaft, F, journaled in suitable boxes, F², secured to the side plate, D, and to the housing A. (See Figs. 1, 2, 4, and 5.) The friction-roller E can be thrown out of or in contact with the roller F' by means of a lever, G, fulcrumed in a frame, G', (see Fig. 1,) and connected at its lower end by means of a rod, H, 40 with the lower end of an arm, I, pivoted to lugs I' of the housing, and connected by its other end to the lower end of the swinging frame C, the connection being made by means

of a pin, C⁴, in the frame, entering slots I² of the arm. Thus it will be seen that by operating the lever the friction-wheels can be brought into and thrown out of engagement. The lever is held to its adjustment by a catch-bar, I³, engaging with the frame by means of notches, as shown in Fig. 1. 50

On the shaft F, and rigidly secured thereto, is a pinion, J, which meshes into two cog-wheels, K L, the former being on a shaft, K', working in journal-boxes K², (see Fig. 5,) and the latter being on a shaft, L', journaled in boxes L². (See Figs. 1 and 5.)

Connected to one of the spokes or arms of the wheel K is an arm, M, the connection being made by a pin, K³, in the spoke entering a slot, M', in the end of the arm. (See Figs. 1 and 3.) The other end of the arm M is connected to a block, N, rocking on a shaft, O, supported by the housing A. (See Figs. 1, 2, and 3.) The rock-block N is also connected to the upper plunger, Q, by a link, P, (see Figs. 2 and 3,) and thus it will be seen that as the wheel K is turned this plunger will be first raised, as shown in Fig. 1, and then compressed, as shown in Fig. 3, and as the pin K³ works in a slot of the arm, there will be a lost motion at each revolution of the wheel, allowing the plunger to remain at rest at short intervals each time it is raised, allowing time for the bricks to be removed and the molds refilled, as hereinafter described. 75

R represents a counterbalance-weight for sustaining the plunger during these intervals. 80

(See Figs. 1 and 3.)

In the same manner that the wheel K is connected to the upper plunger is the wheel L 85 connected to the lower plunger, S, the connecting-arm being lettered S', the rocking block S², its supporting-shaft S³, and the link connecting the block with the plunger, S⁴; but the lower end of this link has a slot, S⁵, through 90 which the connecting-bolt passes, the object being to allow the plunger to be raised, after the rocking block has done its work, by means of a lever-arm, U', fulcrumed on a shaft, U, supported by the housing of the machine and 95 a side plate, A'. (See Figs. 2, 4, and 5.) The

forward end of the arm engages with the plunger. The other end is operated on by a pin, V' , of a wheel, V , on the shaft V^2 journaled in boxes V^3 , secured to the housing. The wheel V is engaged and driven by a pinion, V^4 , on the counter-shaft F . (See Figs. 4 and 5.) Thus when the block S^2 has raised the plunger, as shown in Fig. 3, completing its work, the arm U' is operated as described, carrying the lower plunger up as the upper plunger makes its upward movement, the bricks of course being carried up between them, the lower plunger rising to the top of the molds, and thus neither plunger is pulled away from the bricks while in the molds, causing a strong vacuum and frequent injury to the bricks. This I consider a matter of great practical importance, for the power it requires to pull the plungers away from the bricks, owing to the vacuum necessarily created, is very considerable. As soon as the lower plunger has been raised to the necessary height, the pin of the wheel V slips off the lever U' , and the plunger drops. While the upper plunger is sustained as above described, a charger, W , makes a forward movement, (see Figs. 1 and 3,) shoving the bricks that have just been raised from the molds onto a rest, Y , and filling the molds Z with a fresh charge of clay, and then the charger makes a quick backward movement, to get out of the way of the plunger as it makes its descent. The charger is forced forward by arms W' , to which it is connected by a pin, W^2 , working in slots W^3 of the arms. The arms are rigidly secured to the rock-shaft U , (to which the lever U' is fulcrumed,) and have lower extending ends, W^4 , which are operated on by cams L^4 and V^5 , striking them from beneath, which are secured, respectively, to the shafts L' and V^2 . When the charger has thus been forced forward, it receives a quick backward movement (as soon as the cams leave the arms) by an adjustable counter-balance, W^5 , on an arm or lever, W^6 , rigidly secured to the shaft U . (See Figs. 1, 2, and 4.)

W^7 (see Fig. 2) is a cushioned post, to receive the counter-balance and stop its descent when the charger has been moved back until its receptacles are beneath the hopper W^8 ,

which holds the clay for filling the charger. (See Fig. 3.) When the charger moves forward the second time, it moves the first pair of bricks from the rest Y (see Fig. 1) onto an endless belt, 1, which carries them away, and so on. The belt is driven by a shaft, 2, journaled in the frame, and turned by a chain, 3, connecting it with the shaft F by suitable sprocket-wheels, 4, 5. (See Figs. 4 and 5.)

My machine is designed to make two bricks at a time, so there is a pair of molds, and each plunger has a pair of dies, (see Fig. 7,) and the charger a pair of receiving-receptacles. (See Fig. 6.) The holes S^6 in the lower plunger (see Fig. 7) are to receive the forked end of the lever U' .

In order to make different thicknesses of brick, and have a uniform pressure on all, I provide the lower plunger-dies with removable plates S^7 , (see Figs. 7 and 8,) of different thicknesses.

6 represents strengthening rods or ties connecting the upper part of the machine with the base. (See Figs. 2 and 5.)

I claim as my invention—

1. In a brick-machine, the stationary molds Z , in combination with plungers Q and S , connected to blocks N and S^2 by links P and S' , and coupling links or arms M and S' and drive-wheels K and L , to which the arms are connected, and suitable means for turning the wheels, substantially as shown and described.

2. In a brick-machine, the charger W , operated in one direction by arms W' , pivoted to the shaft U , and cams L^4 V^4 on the shafts L' V^2 , and in the other direction by a counter-balance, W^5 , substantially as shown and described, for the purpose set forth.

3. In a brick-machine, the combination of driving-pulley B and friction-roller E , secured to the swinging frame C , and the friction-roller brought and held in contact with the driving-roller F by pivoted arm I , rod H , lever G , and frame G' , all substantially as shown and described, for the purpose set forth.

ROBT. N. ROSS.

In presence of—

SAML. KNIGHT,
GEO. H. KNIGHT.
